GUN PERFORATOR CARTRIDGE

Wilfred G. Lane, Los Angeles, Calif., assignor to
The Technicraft Engineering Corp., Los Angeles, Calif., a corporation of California

Original application November 12, 1932, Serial No. 642,410. Divided and this application July 16, 1935, Serial No. 31,685

6 Claims. (Cl. 102—12)

My invention relates to cartridges for gun perforators, and in particular constitutes a division of my copending application for Well casing perforator filed November 12, 1932, Serial No. 642,410, Patent No. 2,062,794, Dec. 1, 1936. Among the objects of the present invention are:

First, to provide a cartridge which is adapted to be fired electrically by heating to incandescence a wire imbedded in the explosive charge; Second, to provide a cartridge of this character wherein the fusible wire extends substantially along the axis thereof and from end to end whereby the charge is simultaneously ignited along the length thereof and burns from the center of the cartridge toward the periphery, thereby facilitating rapid and complete ignition of the explosive charge; and

Third, to provide a cartridge of this character, which, being without percussion caps or other detonating means, is particularly safe to handle.

With these and other objects in view as may appear hereinafter, attention is directed to the drawing in which,

Figure 1 is a longitudinal sectional view of a gun unit with my cartridge shown in position and in elevation;

Figure 2 is a front end view of my cartridge; Figure 3 is a longitudinal sectional view thereof taken through 3—3 of Figure 2;

Figure 4 is a transverse sectional view thereof taken through 4—4 of Figure 3; and,

Figure 5 is a rear end elevational view thereof.

As disclosed in my forementioned copending application, the cartridge is adapted to be used

in a gun perforator which comprises generally a cylindrical body adapted to fit within a well

casing and carrying a plurality of laterally di-

rected gun units, which may be removable and

one of which is shown in Fig. 1. The gun body

of the perforator is also provided with an elec-

trically operated controller to which the several

gun units are electrically connected individually.

A special cable with a conductor core both sup-

ports the perforator and supplies electrical energy

to the controller and the several gun units.

As illustrated in Fig. 1, each gun unit comprises

a chamber block 1 having a screwthreaded en-

largement 1a for connection to the gun body, not

shown. The chamber block 1 is bored to form a

cartridge chamber 1b and counterbored and in-

ternally threaded outwardly from the chamber,

as indicated by 1c, to receive a correspondingly

threaded barrel 2. As the gun unit is intended

to be immersed, often to great depths in liquid,

a sealing ring 3 is provided around the breach

end of the barrel. The barrel 2 is provided with a bore 2a therethrough, the muzzle end of which is adapted to be closed by a sealing disk 4. Also, between the breach end of the barrel and chamber 1b there is provided an expansion delaying 5 and pressure localizing disk 5. A small opening which is enlarged adjacent the chamber 1b extends from the chamber rearwardly through the back end of the chamber block 1. Said opening receives an insulated contact pin 6 having a head 6a fitting the enlarged end of the opening. The protruding or other end of the pin 6 is provided with a suitable contact clip 6b for connection with a contact plate, not shown, within the gun body. A bullet 7 fits in the barrel bore 2a. The foregoing construction forms no part of the present invention except as it relates to the cartridge construction set forth hereinafter.

My cartridge is adapted to fit within the chamber 1b and comprises a cylindrical shell 11 of insulating material closed at its ends by disks 12 and 13 also formed of insulating material. The disks 12 and 13 are pressed into the ends of the shell and fit tight enough to withstand handling.

The interior of the cartridge is filled with an explosive 14, preferably a fast burning powder. By reason of the fact that the cartridge is used in a gun unit of extremely short barrel and fired under liquid and sufficient force must be applied to drive a relatively heavy bullet through as many as three strings of casing, it is necessary to pack the explosive quite tightly in the cartridge. This is contrary to conventional practice in standard rifle or pistol cartridges. The packing of the explosive tends to retard its burning.

In order to ameliorate this condition, the explosive is ignited by a fusible wire 17 which extends from end to end of the cartridge and substantially along its axis. Upon completing an electrical circuit through the wire, said wire ignites the explosive throughout the length of the cartridge instead of one end only with the result that the distance which the fire must be propagated is reduced to a minimum.

Each of the disks 12 and 13 is provided with a centrally disposed terminal pin 18 comprising a head 18a at the outer side of the disk and a short stem 18b which extends through the disk and is soldered or otherwise secured to the igniting wire 17. The pin 18 carried by the forward disk 12 is provided with a double ended spring clip 19 while a single end spring clip 20 is secured to the other pin 18. The end of the clip 20 is bent over the head of the corresponding pin 18 and is adapted to engage the head 6a

of the contact pin 6 as shown in Fig. 1, while the clip 19 engages the disk 5 and is grounded thereby to the gun unit and gun body.

Though I have shown and described a particular embodiment of my invention, I do not wish to be limited thereto but desire to include in the scope of my invention such embodiments as are embraced in the appended claims.

I claim:

- 10 1. The combination with a gun unit for gun type well casing perforators, wherein the gun unit is provided with a cartridge receiving chamber, a current supplying contact at one end of the chamber and a grounding means at the opposite end of the chamber, of a cartridge structure comprising: a receptacle adapted to contain a charge of explosive incorporating a cylindrical shell and disk-shaped ends; and a fusible wire extending between the ends of said receptacle and adapted to be heated electrically to ignite the explosive, said fusible wire being longer than said receptacle whereby an end may be separated from the shell to permit filling while remaining attached to said fusible wire.
- 15 2. The combination with a gun unit for gun type well casing perforators, wherein the gun unit is provided with a cartridge receiving chamber, a current supplying contact at one end of the chamber and a grounding means at the opposite end of the chamber; of a cartridge structure comprising: a receptacle incorporating a cylindrical shell and disk-shaped plugging ends all of insulating material and provided with terminals in its ends engageable with said current supplying contact and said grounding means respectively; an explosive charge within the receptacle; and a fusible wire substantially centrally disposed within the explosive charge and joined to the terminals, said wire being longer than said shell whereby one end may be separated from the shell while attached to said wire to permit filling of the receptacle.
- 20 3. The combination with a gun unit for gun type well casing perforators, wherein the gun unit is provided with a cartridge receiving chamber, a current supplying contact at one end of the chamber and a grounding means at the opposite end of the chamber; of a cartridge structure comprising: a receptacle incorporating a shell and plug ends closing the shell and provided with terminals in said ends engageable with said current supplying contact and said grounding means re-

spectively; an explosive charge packed in the receptacle to the extent that its burning rate is impaired; and an igniting wire extending the length of the receptacle and joined to the terminals, said wire disposed substantially centrally with respect to the explosive charge and simultaneously operable throughout its length to ignite the explosive charge in a manner to minimize the length of the fire propagation path, said wire being longer than said shell whereby one end may be separated from the shell while attached to said wire to permit filling of the receptacle.

4. An explosive cartridge comprising: a receptacle adapted to contain a charge of explosive and incorporating a cylindrical shell and disk-shaped ends; and a fusible wire extending between the ends of said receptacle and adapted to be heated electrically to ignite the explosive, said fusible wire being longer than said receptacle whereby an end may be separated from the shell to permit filling while remaining attached to said fusible wire.

5. An explosive cartridge comprising: a receptacle incorporating a cylindrical shell and disk-shaped plugging ends all of insulating material, and provided with terminals in its ends adapted to be connected in an electrical circuit; an explosive charge within the receptacle; and a fusible wire substantially centrally disposed within the explosive charge and joined to the terminals, said wire being longer than said shell whereby one end may be separated from the shell while attached to said wire to permit filling of the receptacle.

6. An explosive cartridge comprising: a receptacle incorporating a cylindrical shell and disk-shaped plugging ends all of insulating material, and provided with terminals in its ends adapted to be connected in an electrical circuit; an explosive charge packed in the receptacle to the extent that its burning rate is impaired; and an igniting wire extending the length of the receptacle and joined to the terminals, said wire disposed substantially centrally with respect to the explosive charge and simultaneously operable throughout its length to ignite the explosive charge in a manner to minimize the length of the fire propagation path, said wire being longer than said shell whereby one end may be separated from the shell while attached to said wire to permit filling of the receptacle.
